PLASTIC SHEET MATERIAL

Arthur D. Sylvester and Arno H. Scheiding, Rowayton, Conn., assignors to L. E. Carpenter & Co., Inc., Wharton, N.J., a corporation of New Jersey

Application November 20, 1956, Serial No. 43,852

Term of patent 14 years

(Cl. D87—3)

Fig. 1.

Fig. 2.

Fig. 1 is a plan view of a piece of plastic sheet material embodying our new design; and

Fig. 2 is a vertical sectional view, taken along the line II—II of Fig. 1.

The instant design comprises a specific pattern, consisting of four major areas, each having the general configuration of a triangle, said areas being arranged so that the bases of the triangles form a rectangular figure, and the other sides of the triangular areas lie along diagonals of the rectangular figure, and a circular area located at the center of the rectangular figure; the portions of the generally triangular areas nearest the center of the rectangle terminating in arcuate edges abutting the periphery of the circular area, each of said areas comprising alternating ridges and grooves concentric

about a point within the area, with the major portion of said ridges and grooves in the triangular areas defining loops in the general form of circles distorted as by stretching toward the apices of the triangles, as shown.

We claim:

The ornamental design for a plastic sheet material, substantially as shown and described.
